tion, New York, N. Y., a corporation of New
York

Application July 9, 1948, Serial No. 37,939

7 Claims. (Cl. 250—27)

1

This invention relates to trigger circuits and more particularly to triggers of the type having two grid controlled tubes and two stable conditions alternately assumed.

In such triggers it is conventional to connect the plate of each tube to the control grid of the other through a resistor and capacitor in shunt. The stable condition of the trigger is switched by the application of pulses to either or both control grids or to either or both plates. As soon as the plate voltage of one tube is changed by a change in the conduction of that tube in response to a pulse of predetermined amplitude, the voltage change is transferred almost instantaneously to the control grid of the other tube. The conductive condition of the latter tube is accordingly changed to switch the trigger to its other stable condition. Since the switching of the trigger from one stable condition to the other requires only the application of a pulse having a certain amplitude, it is difficult to obtain reliable trigger operation when the trigger is necessarily subjected to various transients capable of switching it from one stable condition to the other.

Accordingly, it is a principal object of the invention to provide a novel trigger circuit which requires a pulse of predetermined minimum amplitude and predetermined minimum duration to effect a switching thereof.

It is another object to provide a trigger circuit of high stability which is non-responsive to noise and other unwanted transients.

It is another object to provide a trigger circuit having two tubes and two stable conditions alternately assumed wherein a pulse applied to one tube will effect a switching of the trigger to one stable condition, a pulse applied to the other tube will effect a switching of the trigger to the other stable condition and pulses applied simultaneously to both tubes do not affect the stable condition of the trigger.

It is a further object to provide a trigger circuit having two tubes and two stable conditions wherein the application of pulses to both tubes within a certain predetermined time does not affect the stable condition of the trigger.

It is a further object to provide a trigger circuit having two tubes wherein degenerative feedback is employed to delay the response of the trigger.

It is a still further object to provide a trigger circuit having two tubes wherein the plate of each tube is connected solely through resistance to the control grid of the other.

2

Other objects of the invention will be pointed out in the following description and claims and illustrated in the accompanying drawings, which disclose, by way of example, the principle of the invention and the best mode, which has been contemplated, of applying that principle.

The drawing is a circuit diagram of an embodiment of the novel trigger circuit of the invention.

10 The arrangement of the trigger circuit will be described with reference to the values of applied voltage and the values of resistances and capacitances used. These values are given solely for the purpose of clarifying the explanation, 15 and it is to be specifically understood that they may be varied considerably without departing from the principles of the invention.

Referring more particularly to the drawing, the trigger includes the tubes 10 and 11. These 20 tubes may be of the type in which a single tube is contained in one envelope or of the type wherein the two tubes are contained in the same envelope such as a 6J6.

The plate of each tube 10 and 11 is connected 25 to a +150 volt line through resistors 13 and 14 in series having values of 12,000 ohms and 7,500 ohms, respectively. The cathodes are connected together and through a resistor 15 of 19,700 ohms to a -100 volt line 16. The control grid of the 30 tube 10 is connected through resistors 17 and 18 of 1,000 ohms and 200,000 ohms, respectively, to the -100 volt line 16. Similarly, the control grid of the tube 11 is connected through resistors 19 and 20 of 1,000 ohms and 200,000 ohms, respectively, to the line 16.

The plate of the tube 10 is connected through 35 a lead 21, a resistor 22 of 200,000 ohms and the resistor 19 of 1,000 ohms to the control grid of the tube 11. Similarly, the plate of the tube 11 is connected through a lead 23, a resistor 24 of 200,000 ohms and the resistor 17 of 1,000 ohms to the control grid of the tube 10. The plate of the tube 10 is connected to its own control grid 40 through a lead 25, a capacitor 26 of 0.005 microfarad and the resistor 17. Similarly, the plate of the tube 11 is connected to its own control grid through a lead 27, a capacitor 28 of 0.005 microfarad and the resistor 19.

45 Separate input connections are provided for each tube. Input terminal 29 is connected through a lead 30 and a resistor 31 of 100,000 ohms to the resistor 17 connected to the control grid of the tube 10. Input terminal 29 is also 50 connected to the ground or zero voltage line 32,

through the lead 30 and a resistor 33 of 5,100 ohms.

Input terminal 34 is connected through a lead 35 and a resistor 36 of 100,000 ohms to the resistor 19 connected to the control grid of the tube 11. Input terminal 34 is also connected to the ground or zero voltage line 32 through the lead 35 and a resistor 37 of 5,100 ohms.

An output terminal 38 is connected via line 23 directly to the plate of tube 11 and the output is taken between terminal 38 and the ground line 32.

The two stable conditions of the trigger are designated herein as the "on" and "off" conditions. The trigger is "on," when the tube 10 is conductive and the tube 11 is non-conductive, and the trigger is "off" when the tube 10 is non-conductive and the tube 11 is conductive. For the purposes of explanation, the novel trigger is assumed to be initially "off" (i. e. with tube 11 conducting) as indicated by the dot to the lower right of the tube 11.

Now a positive pulse may be applied to the input terminal 29 and the voltage at the control grid of the tube 10 made sufficiently positive to render the tube conductive. As a result, the voltage at the plate of the tube 10 is decreased and the decreased voltage is transferred through the lead 21 and the resistors 22 and 19 to the control grid of the tube 11 to decrease the conduction of the tube 11. The resulting increased voltage at the plate of the tube 11 is transferred through the lead 23 and the resistors 24 and 17 to the control grid of the tube 10, to render it still more conductive. This cumulative action is continued until the tube 10 reaches a steady state of conduction and the tube 11 becomes non-conductive, to maintain the trigger "on."

Next, a positive pulse may be applied to the input terminal 34 and the voltage at the control grid of the tube 11 is thus made sufficiently positive to render the tube conductive. The resulting decreased voltage at the plate of the tube 11 is transferred through the lead 23 and the resistors 24 and 17 to the control grid of the tube 10 to decrease the conduction of the tube 10. The resulting increased voltage at the plate of the tube 10 is transferred through the lead 21 and the resistors 22 and 19, to the control grid of the tube 11 to render it still more conductive. This cumulative action is continued until the tube 11 reaches a steady state of conduction and the tube 10 becomes non-conductive, to maintain the trigger "off."

The trigger may be switched from one stable condition to the other, by applying positive pulses alternately to the input terminals 29 and 34, respectively.

When pulses are applied simultaneously to the control grids of the tubes 10 and 11, the stable condition of the trigger is not changed. The increased conduction of the initially conductive tube is utilized to buck and prevent a change in the stable condition of the trigger. This action is referred to herein as "bucking action" and the novel trigger arrangement for effecting it is referred to as a bucking trigger.

To make use of this bucking action, the input terminals 29 and 34 are connected together or any conventional means may be employed to apply pulses to these terminals substantially simultaneously. The mere connecting together of the terminals causes no change in the stable condition of the trigger and has substantially no

effect on it, since the terminals 29 and 34 are at substantially the same voltage.

When a positive pulse is applied simultaneously to the terminals 29 and 34, the voltage at the control grids of both tubes 10 and 11 is increased and the stable condition of the trigger remains unchanged because of the bucking action. The increased voltage on the control grid of the tube 11 increases the conduction through that tube and the voltage at its cathode is increased accordingly. Since the cathode of the non-conductive tube 10 is connected to the cathode of the conductive tube 11, the voltage on one cathode is the same as that on the other. However, this increased voltage at the cathode of the tube 10 does not affect the stable condition of the trigger. Though the voltage on the control grid of the tube 10 is increased by the pulse applied, it is insufficient to render the tube 10 conductive because of the increased voltage at the cathode. In other words, when pulses are applied simultaneously to both tubes of the trigger, the bucking action effected by the increased current flow through the conductive tube of the trigger prevents conduction through the non-conductive tube and maintains the trigger in the same stable condition.

The function of the capacitors 26 and 28 connected between the plates and the control grids of the tubes 10 and 11, respectively, is extremely important if the pulses applied to the input terminals 29 and 34 are not applied exactly simultaneously and bucking action is desired. These capacitors provide a degenerative feedback circuit for the respective tubes and tend to maintain them in their present conductive state, resisting any change in the stable condition of the trigger. Hence, the capacitors delay the switching of the trigger from either stable condition to the other. This delay permits a departure from simultaneity or mistiming in the application of pulses to the terminals 29 and 34 without producing a switching of the trigger. The actual departure from simultaneity permitted without sacrificing the bucking action described will vary with the design of each particular trigger. The triggers described, wherein the capacitors 26 and 28 are each of 0.005 microfarad, permits a mistiming in the order of 2,000 microseconds, before the trigger is switched in response to either pulse.

This departure from simultaneity means also that the pulse which will produce a switching of the trigger must have a duration of at least 2,000 microseconds. Hence, pulses having a duration less than 2,000 microseconds though of sufficient amplitude to produce a switching of the trigger are ineffective to do so because of the degenerative feedback. It is clear, therefore, that random noise, supply voltage fluctuations and unwanted transients, which happen to be present because of the particular circuit arrangement with which the trigger is used, do not produce a switching of the trigger from one stable condition to the other.

From the description it is apparent that the trigger of the invention is peculiarly useful for producing ordinary triggering in response to pulses of predetermined characteristics or as a bucking trigger when pulses are received by it simultaneously.

While there have been shown and described and pointed out the fundamental novel features of the invention as applied to a single modification, it will be understood that various omissions and substitutions and changes in the form and details of the circuit illustrated and in its opera-

tion may be made by those skilled in the art without departing from the spirit of the invention. It is the intention, therefore, to be limited only as indicated by the scope of the following claims.

What is claimed is:

1. A trigger circuit having two grid controlled tubes each including a cathode, a grid and a plate, said trigger having two stable conditions alternately assumed; a resistance of 200K ohms connected from the plate of each tube to the control grid of the other; a connection to the control grid of each tube for switching the trigger from either stable condition to the other; and a capacitor of 0.005 microfarads connected from the plate to the control grid of each tube for providing degenerative feedback to resist a change in the conductive state of the tube and thereby delay the switching of the trigger for the order of 2000 microseconds.

2. A trigger circuit having two grid controlled tubes each including a cathode, a grid and a plate, each trigger having two stable conditions alternately assumed; a resistive connection from the plate of each tube to the control grid of the other; a connection to the control grid of each tube for switching the trigger from either stable condition to the other; a capacitive connection from the plate to the control grid of each tube for resisting a change in the conductive state of the tube; a conductive connection between the cathodes of the tubes so that the voltage at each cathode is substantially equal to that at the other at all times; and a resistor connecting the cathodes to a source of voltage whereby the increased conduction through either tube in response to a pulse causes an increased voltage at the cathodes rendering the other tube non-responsive to said pulse.

3. In an electronic circuit having two grid controlled tubes each including a cathode, a grid and a plate, said trigger having two stable conditions alternately assumed; a degenerative feedback circuit coupled between the plate of each tube and its grid, a purely resistive connection between the plate of each tube and the control grid of the other for controlling the conductive state of each tube in accordance with the plate voltage of the other; and a conductive connection between the cathodes of the two tubes for equalizing the voltages on said cathodes and for preventing the conduction of one tube when the conduction of the other is increased.

4. A trigger circuit including two grid controlled tubes each including a cathode, a grid and a plate and each having its plate connected through a load to a positive voltage source said trigger having two conditions of stability alternately assumed, a resistive connection only between the plate of each tube and the control grid of the other, a degenerative coupling between the plate of each tube and its grid, a common cathode

resistance connecting the cathodes of said tubes to a negative voltage source, a bias resistance between the control grid of each tube and said negative voltage source, a first input terminal resistively connected to the control grid of one tube for applying positive pulses thereto and resistively connected to a zero voltage line, a second input terminal resistively connected to the control grid of the other tube for applying positive pulses

thereto and resistively connected to a zero voltage line whereby the trigger is switched from each condition of stability to the other alternately only in response to pulses applied alternately to said input terminals.

5. The trigger circuit set forth in claim 4, wherein a capacitive connection is provided between the plate of each tube and its control grid for resisting a change in the conductive state of the respective tubes.

6. A bucking trigger circuit having two grid controlled tubes, each including a cathode, a grid and a plate, said trigger having two stable conditions alternately assumed in response to pulses, wherein pulses applied simultaneously to an electrode of each tube do not produce a change in the stable condition of the trigger, including a resistive connection from the plate of each tube to a grid of the other for controlling that grid voltage of each tube in accordance with the plate voltage of the other, a capacitive connection from the plate of each tube to a grid thereof and means for maintaining voltage equalization between corresponding cathodes of said tubes for preventing a change in the stable condition of the trigger when pulses are applied simultaneously to both tubes, said means including a conductive connection between said cathodes.

7. A trigger circuit having two grid controlled tubes each including a cathode, a grid and a plate, said trigger having two stable conditions alternately assumed; a purely resistive connection from the plate of each tube to the control grid of the other, connections to the control grid of each tube for switching the trigger from either stable condition to the other and a capacitive connection from the plate to the control grid of each tube for resisting a change in the conductive state of the tube.
